CLAIM

The ornamental design for a boot rack, as shown and described.

DESCRIPTION

FIG. 1 is a front elevational view of a boot rack showing my new design;

FIG. 2 is a right side elevational view of a boot rack, the left side being a mirror image thereof;

FIGS. 3 and 4 are respectively top and bottom plan views thereof;

FIG. 5 is a back view of a boot rack;

FIG. 6 is a front elevational view of a second embodiment of my boot rack;

FIG. 7 is a right side elevational view of the second embodiment of my boot rack, the left side being a mirror image thereof;

FIGS. 8 and 9 are respectively top and bottom plan views thereof;

FIG. 10 is a back view of the second embodiment of my boot rack;

FIG. 11 is a front elevational view of a third embodiment of my boot rack;

FIG. 12 is a right side elevational view of the third embodiment of my boot rack, the left side being a mirror image thereof;

FIGS. 13 and 14 are respectively top and bottom plan views thereof;

FIG. 15 is a back view of the third embodiment of my boot rack;

FIG. 16 is a front elevational view of a fourth embodiment of my boot rack;

FIG. 17 is a right side elevational view of the fourth embodiment of my boot rack, the left side being a mirror image thereof;

FIGS. 18 and 19 are respectively top and bottom plan views thereof; and,

FIG. 20 is a back view of the fourth embodiment of my boot rack.
